UNITED STATES PATENT OFFICE

FRANCIS G. GRAVES, OF ALAMEDA, CALIFORNIA, ASSIGNOR TO STANDARD OIL COMPANY OF CALIFORNIA, OF SAN FRANCISCO, CALIFORNIA, A CORPORATION OF DELAWARE

PROCESS OF TREATING PETROLEUM OILS

Application filed March 2, 1927. Serial No. 171,951.

This invention relates to improvements in processes of treating petroleum oils, and refers more particularly to a process of treating petroleum oils to remove gum-forming bodies to deodorize, decolorize, and desulfurize relatively light petroleum distillates, particularly those distillates which are at this time employed as fuel for internal combustion engines.

10 It is well known that distillates used for motor fuels and illuminating purposes contain, prior to suitable treatment, undesirable products which would render the distillate unfit for use if not removed. It has been 15 heretofore common practice to remove the undesirable products such as sulfur compounds, resins, gums, water, or other objectionable products using many divers processes. The customary treatment for the removal of these 20 products consists in a series of applications of sulfuric acid, sodium hydroxide, and water, which treatments may or may not be followed by redistillation. Resort has also been had to the use of metals or metallic salts to 25 remove from certain oils which are particularly difficult to refine sulfur and sulfur compounds.

In addition to those impurities which can be removed by the usual acid with caustic 30 treatment or simple application of metals or metallic salts, there are in some distillates, such as those obtained by cracking a typical California crude petroleum oil, certain gum-forming bodies which cannot be entirely removed by the usual methods. The presence 35 of these gum forming bodies can be readily determined by the well known copper bowl test.

I have discovered that light distillates may 40 be made to pass a satisfactory copper bowl or gum test if they are first contacted with a metallic copper and then contacted with an absorbent material. The absorbent material may be of the type commonly known as "contact clays", many of which are mined in California, and of which Otay clay and Janney clay are examples, or such minerals as montmorillonite or fuller's earth. The action of 45 the copper upon the gum forming bodies of the light distillates is apparently to poly-

merize them so that they can be subsequently removed by the absorbent material. The treatment of oils by copper alone or by an absorbent agent alone will not effect the removal of the gum-forming bodies from certain oils so that the oils will pass a satisfactory gum test; however, I have discovered that the combined treatment with copper and clay effects a substantially complete removal of the gum-forming bodies from these oils.

In the drawing, I have illustrated one form of apparatus that may be employed for carrying out the process embodying this invention, and wherein 1 indicates a source of feed which may be any suitable petroleum oil 45 distillate. The petroleum distillate is pumped by a feed pump 2 through a pre-heater 3 to one or more treaters 4 and 5. Valves 6 and 7 are provided in the inlet and outlet lines 8 and 9, respectively, of the 50 treaters 4 and 5 so that the pressure in these treaters may be raised by raising the temperature in the treaters by any suitable means (not shown). The treaters 4 and 5 may be filled with copper turnings or copper in any 55 suitable comminuted form, as illustrated at 10, so as to present a large reacting surface to the distillate. The distillate is maintained in the treaters 4 and 5 until the gum-forming bodies have been polymerized as determined 60 by tests made by treating samples with clay. The distillate is then passed through the conduit 11 into a mixing tank 12 and mixed with contact clay from a storage tank 13, fed into the mixer 12 by means of a conveyor 14. Any suitable or desirable means may be employed for agitating or thoroughly commingling the clay and distillate in the mixing 65 tank 12.

After the distillate has been thoroughly contacted with the clay in the mixing tank 12, the same is passed by means of a pump 15 into a still 16. Any suitable form of agitating means, such as illustrated at 17, may be employed for agitating the mixture within the still 16 and the means 17 are herein illustrated as comprising a screw agitator or scraper 18 driven by a pulley 19 from any suitable or desirable source of power.

Heat is applied to the still by external firing means or by any other means, as desired.

A fractionating tower 20 of any suitable or desirable form is provided on the still 16 from which the desired vapors pass through a condenser 21 into a storage tank 22. The draw-off line 23 is provided at the bottom of the still 16 for the removal of the clay and bottoms.

10 In many cases it is believed advisable to treat the distillate after the same has been distilled off the contact clay with caustic (sodium hydroxide, potassium hydroxide, etc.). This may be done by introducing the caustic into the vapor line that leads from the still 16 to the condenser 21 in any desired or preferred manner as is well understood in the art.

20 While the apparatus hereinbefore set forth is exceedingly well adapted for carrying out the process embodying this invention, it is to be understood that the process embodying this invention may be accomplished by either batch or continuous operation. The use of heat and super-atmospheric pressure during the copper treating step of this process has been found to be extremely advantageous.

30 In carrying out the process embodying this invention by the batch operation, the batch treatment can be carried out either by refluxing the distillate over copper or in a closed system under pressure.

35 The time of treatment of the distillate with the copper has been found to vary, depending upon the amount of copper used and it has also been found that the action of the copper on the distillate to remove or polymerize the gum-forming bodies is increased by increasing the temperature of the distillate during the treatment.

40 The continuous process is preferably carried out entirely in a closed system.

45 During the treatment of the distillate with copper, it has been found that the copper becomes coated with sulfide and oxide which may be rendered fit for further use by washing from time to time with dilute sulfuric acid.

50 The clay treatment which follows the copper treatment may be carried out in several different ways, as follows:

55 1. The contact clay may be introduced directly into the still together with the oil which has been previously copper treated, and the desired boiling point stock distilled off by direct fire distillation or other application of heat.

60 2. The distillate may be contact treated with the contact clay applied to the distillate in the liquid phase as, for example, in the mixer tank 12.

65 3. The distillate in the vapor phase may be contacted with the contact clay in any suitable or desirable manner.

4. It is also understood that substantially

the same results may be obtained by percolation of the distillate through fuller's earth in the liquid phase or in the vapor phase.

70 The last three mentioned methods of clay application or treatment may be followed by steam distillation of the product to obtain a final product having the boiling point range desired.

75 It will be obvious from the foregoing that by the present process, the gum-forming bodies present in a distillate are polymerized and subsequently removed so that the final products will give no gumming in the copper bowl test. In accordance with this process, there is also produced a gasoline or motor fuel which is non-corrosive, and a water-white, stable colored product which is lower in sulfur content than the original product and which will give an improved "doctor test".

80 Having fully described the present invention, it is to be understood that the same is of the scope of the appended claims.

85 I claim:

90 1. A process of treating petroleum distillates containing gum-forming bodies, comprising the steps of contacting a distillate containing gum-forming bodies at a temperature above atmospheric with metallic copper in the absence of appreciable amounts of copper oxide, separating the treated distillate from the copper, and then contacting the treated distillate, at a temperature above atmospheric, with an adsorbent clay.

95 2. A process of treating petroleum distillates, consisting of heating a distillate containing gum-forming bodies, contacting the heated distillate with metallic copper in the absence of appreciable amounts of copper oxide to polymerize such gum-forming bodies, separating the treated distillate from the metallic copper, then mixing the treated distillate with an adsorbent clay, and finally distilling the distillate from the mixture.

100 3. In a process of treating petroleum distillates containing gum-forming bodies, the steps of heating a distillate containing gum-forming bodies, contacting the heated distillate under pressure with metallic copper in the absence of appreciable amounts of copper oxide to polymerize such gum-forming bodies, separating the treated distillate from the metallic copper, and then contacting the treated distillate at superatmospheric temperature with an adsorbent clay.

110 4. A process of treating petroleum distillates containing gum-forming bodies, consisting of contacting a distillate containing gum-forming bodies at a temperature above atmospheric with metallic copper in the absence of appreciable amounts of copper oxide to remove and polymerize said bodies, separating the treated distillate from the metallic copper, then contacting the treated dis-
